UNITED STATES PATENT OFFICE.

GEA C. BROWN AND GREGORY F. McNULTY, OF MASSILLION, OHIO, ASSIGNEES TO THE REYNOLDS MACHINE COMPANY, OF MASSILLION, OHIO, A CORPORATION OF OHIO.

SCREW-DRIVING MACHINE.

Application filed November 2, 1925. Serial No. 66,223.

The invention relates to mechanism for driving screws and more particularly to an automatic multiple spindle machine.

The object of the present improvement is to provide a screw driving machine having a plurality of driving spindles and provided with one or more magazines which simultaneously feed screws to the several spindles, all of the spindles being simultaneously operated to drive the plurality of screws at one time; means being provided for compensating for variation in the lengths of time to drive the several screws; a work carrying table being provided upon the machine and arranged to be automatically raised as the mechanism is put into operation.

An embodiment of the invention is illustrated in the accompanying drawings, in which:

Fig. 1 is a front elevation of the improved screw driving machine;

Fig. 2, a side elevation of the same with parts broken away;

Fig. 3, a plan section on the line 3—3, Figure 1, upon a larger scale;

Fig. 4, a vertical sectional view through one of the chucks showing the compensating means upon the driving spindle;

Fig. 5, a plan sectional view of one of the screw magazines and the multiple feeding mechanism;

Fig. 6, a vertical sectional view of the same;

Fig. 7, a detail perspective view of the escapement mechanism, showing a fragmentary portion of the feed magazines;

Fig. 8, a detail perspective view of the cam blade;

Fig. 9, a plan view of the escapement mechanism in the cut-off position;

Fig. 10, a similar view of the escapement mechanism in the position just prior to releasing a screw, and

Fig. 11, a perspective view of the gearing by means of which the several parts of the mechanism are driven.

Similar numerals refer to corresponding parts throughout the drawings.

The mechanism is carried by a standard 1 having the enlarged base portion 2, upon the rear portion of which may be mounted the motor 3 for driving the mechanism. A pinion 4, upon the motor shaft 5, meshes with a gear 6, upon a short horizontal shaft 7, said shaft being provided with a bevel pinion 8 meshing with a bevel pinion 9 upon the ver-

tical shaft 10 which extends upward through the hollow standard 1, the bevel pinions being preferably located within a housing 12.

Although any desired number of screws may be simultaneously driven by a machine of this character, the particular machine illustrated in the accompanying drawings is designed for driving four screws at one time. For this purpose four driving bits are required and the machine is provided with two magazines each of which feeds the screws to two of the driving bits.

Each of the magazines 13 is rigidly supported at one side of the standard 1, as by a bracket 14. These magazines are substantially circular in plan view, and each comprises an annular side wall provided with an arch or spider 15 which supports the bearing 16 for the spindle 17 upon the lower end portion of which is fixed the conical dial 18 having a hub 19 fixed upon said spindle.

The dial 18 is inclined downward toward its periphery, which is located in the same horizontal plane with the beveled annular flange 20 in the lower edge of the magazine side wall, and spaced therefrom a distance corresponding to the diameter of the shanks of the screws to be deposited therein. The circumferential edge of the dial is likewise beveled, upon its upper face as shown at 21, corresponding with the bevel of the flange 20.

The periphery of the dial 18 is thus spaced sufficiently from the flange 20 to provide a circular space or runway into which the shanks of the screws, supplied to the magazine, fall, and are suspended by reason of the heads thereof resting on the beveled edge of the dial and the flange 20.

Mounted upon diametrically opposed portions of the side wall of the magazine are bearings 24 within which are journaled shafts 25 carrying the circular brushes 26, the diameter of each brush being such that it will brush back any surplus screws which may be carried forward by the dial, allowing only those screws to pass which are suspended by their heads in the annular runway.

A guard ring 27 is connected to the inner wall of the magazine, slightly above the flange 20, and extends from a point beneath the center of each brush to a point just beyond the co-operating escapement mechanism, which will be later described.

This guard ring is spaced, above the flange 20,

20 and the periphery of the rotating dial 18, a sufficient distance to permit the heads of the screws to pass freely beneath the same when the screws are hanging vertically in 5 the annular runway, but is sufficiently close to the runway to prevent any screws passing beneath the ring excepting those which are suspended in the proper position.

A worm wheel 28 is carried by each brush 10 shaft and meshes with a worm 29 upon a worm shaft 30, each of these worm shafts having a spiral gear 31 which meshes with a spiral gear 32 upon the magazine drive shaft 33 located transversely through the 15 machine and driven by the main drive shaft 10.

The upper end of the main drive shaft 10 is provided with a bevel gear 34, meshing with a bevel gear 35 upon the horizontal 20 shaft 36. A counter shaft 37 is driven from the shaft 36 through the gears 38. A gear 39 is mounted upon the shaft 37 and meshes with a gear 40 upon the short vertical shaft 41 which drives the shaft 33 through the 25 gearing 42.

For the purpose of permitting a discharge of the pendent screws, one at a time, into the tubes 43, which lead to the chucks 44, an escapement mechanism is provided upon each 30 side of each magazine, at points substantially halfway between the brushes 19.

Each escapement mechanism is mounted in a case 45, which is of channel shape in cross section and connected at its inner end to the 35 lower edge of the magazine wall. As best illustrated in Fig. 5, these escapement cases are preferably located at an angle to a radius of the magazine, and the inner end of each case is angularly recessed, as shown at 46, 40 to receive the screws from the annular runway.

An escapement finger 47 and a cut-off finger 48 are slidably mounted within the escapement case, the finger 47 being provided 45 with the curved recess 49 at its inner extremity to receive the screws, one at a time, as they enter the escapement case, while the cut-off finger 48 is provided with the beveled inner extremity 50 for the purpose of cutting off the admission of screws to the escapement case after one screw has been released by the escapement finger.

The escapement and cut-off fingers are recessed upon their adjacent faces, as indicated 55 at 51, to permit of longitudinal movement of the fingers upon each side of the cam blade 52, and vertically disposed grooves 53 and 54 are provided in the escapement and cut-off fingers, respectively, to receive the escapement cams 56, one of which is provided upon each side of the cam blade 52.

A roller yoke 57 is located upon the escapement casing, the roller 58 being journaled therein and engaging the outer edge of the 60 cam blade 52, and an operating rod 59 is

connected to the upper end of each cam blade and arranged to be reciprocated, as will be later described.

For the purpose of operating the screw driving bits a short vertical shaft 60 is rotated from the shaft 36, as by the bevel pinions 61 and provided at its lower end with a gear 62. This last named gear is located within a housing 63, supported in front of the standard 1, a plurality of sleeves 64, corresponding in number to the screw driver bits, being journaled in said housing, each of the sleeves being provided with a pinion 65 meshing with the gear 62.

A shaft 65^a is journaled through each 80 sleeve and provided at its upper portion with a friction disk 67 arranged to be normally held in frictional engagement with the friction disk 66, upon the upper end of the sleeve, by means of a coil spring 68, whereby motion 85 is transmitted, by friction, from each sleeve to the corresponding shaft 65^a.

The chucks 44 are carried upon a rigid bracket 70, fixed upon the front side of the standard 1, and the screw driving bits 71 are 90 mounted for rotation and vertical movement within said chucks. The bits are journaled in a vertically reciprocating crosshead 72, and for the purpose of compensating for variation in the lengths of the screws or a difference in the time when the various screws take hold in the material into which they are being driven, each bit is formed of two sections having longitudinal movement therebetween.

The upper section 73 of each bit is journaled in the crosshead and has a sleeve 74 fixed to its lower portion, the lower extremity of said section having a half-round lug 75, engaging a similar lug 76 upon the upper end 105 of the bit proper.

A shoulder 77 is formed upon the bit, within the sleeve 74, and a spring 78 is located within the sleeve and engages said shoulder, normally holding the sections 71 and 73 110 apart, and holding the shoulder 76 in engagement with the nut 79 in the lower end of the sleeve.

The upper end of each section 73 is connected to the corresponding spindle 65^a by 115 means of a telescoping spindle 80, universal joints 81 being provided at each end thereof, whereby the screw driving bits may be spaced apart in any desired arrangement regardless of the location of the spindles 65^a.

Each chuck 44 is provided with a vertical bore, in which may be located a bushing or 120 filler tube 82 within which the corresponding screw driving bit 71 is rotatably and slidably located. Each tube or chute 43 leads from the adjacent magazine to one of the chucks, the bushing being cut away to permit screws from the chute to enter the bore.

The lower end of the bushing or filler tube 130 is extended below the lower extremity of the

chuck and provided with diametrically opposed openings 83 to permit the entrance of the inturned lower ends 84 of the jaws 85.

These jaws consist of elongated strips of metal fulcrumed intermediate their extremities, as at 86, upon flanges 87 formed upon the sides of the chuck.

A coil spring 88 is placed between the upper end of each jaw and the adjacent side of the 10 chuck to keep the lower ends of the jaws normally pressing in toward each other.

Semi-funnel shaped grooves 89 are formed in the opposing faces of the lower extremities of the jaws, and when a screw is fed to the 15 chuck the screw threaded point thereof enters this funnel shaped opening and the jaws are forced apart as the screw is forced down between them by the bit, the jaws holding the screw straight and steady while it is being 20 driven into the work.

The operating treadle 90 is pivoted within the standard 1, as at 91, and intermediate its extremities is pivotally connected, as at 92, to a vertical rod 93. A spreader 94 is connected to the upper end of the rod 93 and two vertical rods 95 are connected at their lower extremities to opposite ends of the spreader and extend upward through the standard 1, emerging therefrom at a point spaced from 30 the top, as through the bearing bosses 96.

The tie bar 97 is connected to the upper ends of the rods 95 and provided with a depending lug 98 to which is pivoted one end of a lever 99, the opposite end thereof being pivoted to 35 a stationary portion of the standard as at 100.

A lever 101 is pivoted intermediate its extremities to the upper end of an upright link 102, the lower end of the link being pivotally connected at 103 to the standard. This lever 40 is connected, at a point between its fulcrum and its forward end, to a link 104, the lower end of said link being pivotally connected to the lever 99, intermediate the extremities thereof.

45 The forward end of the lever 101 is connected to the central portion of a transverse spreader or cross arm 105, from the extremities of which depend the rods 106, the lower ends of said rods supporting the crosshead 72.

50 An arm 107 is fixed to each rod 106, and provided at its outer extremity with a T head 108 to the ends of which are fixed the rods 59, which operate the cam blades of the escapement mechanisms.

55 The rear end of the lever 101 supports the depending rod 109 which carries a counter-weight 110. The work carrying table 111 is slidably mounted upon guides 112, formed upon the front faces of the standard, and may 60 be adjustably supported upon the rod 113, by means of the spiral gearing 114 arranged to be manually adjusted as by the crank 115.

65 The lower end of the rod 113 is connected to the substantially horizontal arm 116 of a bell crank, pivoted at 117 upon the standard,

and provided with the depending arm 118 having a cam surface 119 at its upper portion and the arcuate surface 120 at its lower portion, said arc being substantially drawn from the center 91. A roller 121, upon the treadle 70 90, is arranged to engage the surface of the depending arm 118 of the crank.

With each depression of the treadle 90 the work table 111 is raised until the roller 121 rides off of the cam surface 119 of the bell 75 crank, after which the roller rides upon the arcuate surface 120 thereof, holding the table in the raised position. At the same time the forward end of the lever 101 is pulled down through the rods 93 and 95 and lever 99 and link 104, simultaneously operating all of the escapement blades to drop one screw from each side of each magazine through the corresponding tube or chute 43 into one of the chucks. At the same time the screw driver 80 bits are brought down through the chucks, into engagement with the screws simultaneously driving all of the screws into the work.

The compensating means, shown in Fig. 4 of the drawing, allows for any variation in 90 the lengths of the different screws or any variation in the time at which the different screws take hold in the work, thus permitting each screw to be properly driven home after which the friction drive of the screw driving 95 spindles prevents further rotation of the spindles.

As the treadle 90 is released, and permitted to raise, the escapement and screw driving mechanism will be raised to the normal position while the table will be lowered permitting the finished work to be easily removed and new work to be placed thereon.

We claim:

1. A screw driving machine including a 105 magazine for containing screws, a plurality of escapement means associated with the magazine, a chuck communicating with each escapement means, a screw driving bit rotatably and slidably located in each chuck, 110 means for simultaneously operating said escapement means, to admit screws to the chucks, and lowering the driving bits through the chucks, and means for compensating for variation in the lengths of time 115 to drive the several screws.

2. A screw driving machine including a plurality of chucks, a screw driving bit rotatably and slidably located in each chuck, 120 means for simultaneously admitting a screw to each chuck, means for simultaneously operating all of the bits and means for compensating for variation in the lengths of time to drive the several screws.

3. A screw driving machine including a 125 plurality of chucks, a screw driving bit rotatably and slidably located in each chuck, means for simultaneously admitting a screw to each chuck, means for simultaneously operating all of the bits and a spring pressed sec- 130

tion in each bit for compensating for variation in the lengths of time to drive the several screws.

4. A screw driving machine including a magazine for containing screws, a plurality of escapement means associated with the magazine, a chuck communicating with each escapement means, a screw driving bit rotatably and slidably located in each chuck, means for simultaneously operating said escapement means, to admit screws to the chucks, and lowering the driving bits through the chucks, and a spring pressed section in each bit for compensating for variation in the lengths of time to drive the several screws.

5. A screw driving machine including a magazine for containing screws, a plurality of escapement means associated with the magazine, a vertically reciprocating operating blade for each escapement means, a chuck communicating with each escapement means,

a screw driving bit rotatably and slidably located in each chuck, means for simultaneously reciprocating all of said blades and bits, and means for compensating for variation in the lengths of time to drive the several screws.

6. A screw driving machine including a magazine for containing screws, a plurality of escapement means associated with the magazine, a vertically reciprocating operating blade for each escapement means, a chuck-communicating with each escapement means, a screw driving bit rotatably and slidably located in each chuck, means for simultaneously lowering all of said blades and bits, and means for compensating for variation in the lengths of time to drive the several screws.

In testimony that we claim the above, we have hereunto subscribed our names.

GRA C. BROWN.
GREGORY F. McNULTY.
